UNITED STATES PATENT OFFICE.

SIDNEY D. WALDON, OF DETROIT, MICHIGAN, ASSIGNOR TO PACKARD MOTOR CAR COMPANY, OF DETROIT, MICHIGAN, A CORPORATION OF MICHIGAN.

CARBURETER.

1,220,478.

Specification of Letters Patent. Patented Mar. 27, 1917.

Application filed April 15, 1912. Serial No. 690,847.

To all whom it may concern:

Be it known that I, SIDNEY D. WALDON, a citizen of the United States, and resident of Detroit, county of Wayne, and State of Michigan, have invented certain new and useful Improvements in Carbureters, of which the following is a specification.

This invention relates to hydrocarbon motors and more particularly to the carbureter and means for controlling the air and hydrocarbon supply thereto.

The principal object of the invention is to produce a carbureter that will supply the proper mixture of hydrocarbon and air 15 to the motor at all speeds of the motor and under all climatic conditions.

It is a well known fact that the ordinary type of carbureter works best in warm weather and it is the object of this invention 20 to so construct and arrange the parts of the carbureter as to reproduce as nearly as may be summer conditions in and around the carbureter.

Other objects and the features of novelty 25 of the invention will be apparent from the following description taken in connection with the accompanying drawings, in which,

Figure 1 is a vertical sectional view of the carbureter shown in connection with 30 fragments of the intake pipe and exhaust header of the hydrocarbon motor; and

Fig. 2 is a plan of the float chamber casting of the carbureter.

In the drawings, 10 indicates the intake pipe of a hydrocarbon motor and 11 the exhaust header of the same. Communicating with the intake pipe 10 is a mixing chamber 12 which is surrounded by a water jacket 13. The mixing chamber 12 has the lower portion thereof extending horizontally, as indicated at 14, and in communication with the usual choke tube 15. The choke tube 15 may be of any preferred construction and is preferably arranged centrally of the float chamber 16. The float chamber 16 is preferably cylindrical in form and has an extension 17 at one side thereof in which is arranged the hydrocarbon supply valve 18. A partition 19 is arranged 45 in the lower part of the extension 17 and forms a chamber 20 with which the supply pipe 21 communicates. The partition 19 may be provided with a port 22 in which is arranged a suitable seat for the valve 18. 50 An annular float 23 is arranged in the float

chamber 16 and surrounds the choke tube 15. The float 23 is connected with one end of the lever 24, said lever being pivoted at 25 and having its opposite end connected with the valve 18. Arranged at one side 60 of the float chamber 16 is the main air supply passage 26. This passage preferably extends vertically along the side of the chamber 16 and has its lower end turned horizontally and in communication with the 65 lower end of the choke tube 15. A passage 27 leads from the bottom of the chamber 16 to a point below the horizontal portion of the passage 26 and is separated from the latter passage by the wall 28. A nozzle 70 29 extends longitudinally of the choke tube 15 and has its lower end extending through the wall 28 and in communication with the passage 27. The nozzle 29 may have a screw threaded connection with the wall 28 and for the purpose of inserting and removing said nozzle a plug 30 may be arranged in the outer wall of the passage 27. The upper end of the nozzle 29 is preferably arranged in the contracted portion of 75 the choke tube 15 and on a level with the surface of the hydrocarbon in the chamber 16. For the purpose of draining the passage 26 a suitable valve 31 may be arranged at the lowest point of said passage. 80

The mixing chamber casting is preferably provided with a partition 32 which separates the horizontal portion 14 of the mixing chamber from the passage 33 and a partition 34 arranged at the end of the horizontal 90 portion 14 of the mixing chamber separates the latter from the air supply passage 35. A valve cage 36 is secured in the mixing chamber casting and carries an auxiliary air inlet valve 37 arranged directly above the choke tube 15 and in close proximity to the upper end of the same. The valve cage 36 is provided with a suitable seat for the valve 37 and also with openings 38 in its wall adapted to establish communication between the passage 33 and the interior of the cage above the valve 37. A stem 39 is secured to the valve 37 and has at its upper end an abutment 40 which is engaged by a spring 41, the lower end of this spring bearing against a beveled collar 42 which is slidably arranged on a sleeve 43. A spring 44 surrounds the stem 39 within the spring 41 and has its lower end in engagement with the upper end of the sleeve 43. The upper 100 105 110

end of the spring 44 is arranged to be a slight distance below the abutment 40 when the valve 37 is closed. The lower end of the sleeve 43 is beveled and coöperates with a wedge 45 which is slidably arranged on the upper side of the cage 36. An abutment 46 is arranged on the top of the cage 36 above the wedge 45 and supports a wedge 47 which coöperates with the beveled collar 42. The 10 tension of the spring 41 and the point at which the spring 44 becomes active may be varied by means of the wedges 47 and 45 respectively. For the purpose of actuating the wedges 45 and 47, the operating rods 48 and 49 are connected with the wedges and may extend to any convenient point.

In the outer wall of the passage 33 is an auxiliary air opening 50. Adjacent this opening is a flap valve 51 which is adapted 20 to be swung across the passage 33 to close the opening 50 or cut the passage 33 off from the passage 35. The valve 51 has an operating arm 52 connected therewith, this arm being connected with an operating rod 53. It will be seen that by this construction 5 the valve 51 may be swung to various intermediate positions so that the passage 33 may be partially in communication with the opening 50 and with the passage 35. A 30 hood or guard 54 may be arranged over the opening 50.

Surrounding the exhaust header 11 is a jacket 55 which provides an annular chamber around the header. The jacket 55 may 35 be provided with perforated end walls 56 and 57 which permit air to pass freely to the interior of the jacket. A pipe 58 has one end in communication with the interior of the jacket 55 and has its other end in communication with the chamber 35. At any 40 convenient point along the pipe 58 may be arranged a sleeve valve 59 having openings 60 which are adapted to register with corresponding openings in the pipe 58. It will thus be seen that the pipe 58 serves as an 45 air supply pipe to the carbureter and that the pipe receives air from the interior of the jacket 55. In the operation of the engine the exhaust header is ordinarily in a highly 50 heated condition and the air passing through the jacket 55 will therefore be heated to a considerable degree and thus be delivered to the carbureter at a much higher temperature than the external atmosphere. In order 55 to regulate the temperature of the air delivered to the carbureter, the valve 59 may be adjusted to admit cold air directly to the pipe 58 where it mixes with the hot air from the jacket 55, and reduces the 60 temperature.

In constructing the carbureter I prefer to make the float chamber casting separate from the mixing chamber casting and secure the two together in any suitable manner. 65 The pipe 58 is also preferably separate from

the mixing chamber casting and secured to the latter by means of the flanges 61 and 62 and the screws 63.

The operation of the carbureter is as follows: The hydrocarbon or gasoline is supplied to the chamber 20 by means of the pipe 21 from any suitable storage tank. When the valve 18 is open the gasoline passes into the float chamber 16 and fills the same to a point where the flange 18 is closed by the 75 float 23. The gasoline will fill the passage 27 and rise in the nozzle 29 to the upper end of the latter. Since the upper end of the nozzle 29 is substantially on a level with the gasoline in the chamber 16, it will be 80 seen that when the pressure in the mixing chamber 12 and choke tube 15 is reduced by the motor suction, the gasoline will be discharged from the upper end of the nozzle 29 and air be drawn through the choke tube 85 and mixed with the gasoline. The air passing through the choke tube 15 is supplied by the passage 26 which in turn is supplied from the pipe 58. The air passing through the pipe 58 will be heated in the jacket 55, 90 and have a temperature which will effect a thorough vaporization of the gasoline.

The effect of the motor suction may be regulated by means of the butterfly throttle valve 64 arranged in the upper part of the 95 mixing chamber 12. When it is desired to start the motor it is preferable to have the throttle 64 wide open and to limit the supply of air to the choke tube. The supply of air to the choke tube may be regulated 100 by means of a butterfly throttle valve 65 arranged in the passage 26. In order to prevent a complete closure of the passage 26, the throttle 65 may be provided with a small opening 66 which will always allow a small 105 amount of air to pass therethrough. When the motor is running at moderate speeds all of the air will be drawn through the passage 26 and the choke tube 15 but when the motor is running at high speeds the suction will 110 overcome the tension of the spring 41 and open the auxiliary air inlet valve 37 thereby admitting air directly to the mixing chamber 12. As the suction increases the quantity of gasoline discharged by the nozzle 29 115 also increases and therefore it is desirable to have under such circumstances means for effectively atomizing the gasoline. From the drawing it will be seen that the current of air and gasoline delivered from the choke 120 tube 15 will strike the lower side of the valve 37 and cause the gasoline to be so thoroughly atomized that it will form a perfect mixture with the air passing through the choke tube and the auxiliary valve 37. By having the 125 auxiliary valve located directly over the outlet end of the choke tube, the valve not only acts as a baffle to thoroughly break up and atomize the gasoline, but also tends to limit the quantity of air passing through the 130

choke tube as the quantity passing through the auxiliary valve increases.

In Fig. 1 this is clearly illustrated by indicating the valve 37, in open position, in dotted lines. With the valve 51 in the position shown in Fig. 1 and the auxiliary valve open, it will be seen that the air passing through the choke tube will be received from the pipe 58 and will ordinarily be of considerably higher temperature than the external atmosphere, but the air passing through the auxiliary valve 37 will be received through the opening 50 and the passage 33 and will be of substantially the same temperature as the external atmosphere. If it is desired to have all of the air with which the gasoline is mixed as hot as possible, the valve 51 will be swung upwardly from the position shown in Fig. 1 to the position where it closes the opening 50 and thus establishes communication between the passage 33 and the pipe 58. In this position of the valve 51 all of the air passing through the auxiliary valve as well as the air passing through the choke tube will be derived from the pipe 58. From the two extreme positions of the valve 51 above mentioned, it will be seen that this valve may be set at any desired intermediate position and thereby regulate the temperature of the air passing through the auxiliary valve 37.

By having the upper end of the spring 44 arranged a slight distance below the abutment 40, this spring will act as a buffer and tend to limit the amount of opening of the valve 37. However the tension of the spring 44 will be such that when the motor is running at very high speeds this spring will also be compressed and permit the valve 37 to be opened to the extent necessary to supply the required amount of air to the mixing chamber 12.

When the carbureter is used on a motor vehicle, the throttle 65 is preferably operated by means of a rod 67 which extends to any convenient point at the front of the vehicle, and the rods 48, 49 and 53 extend to the dash of the vehicle where they may be conveniently operated.

Ordinarily when the motor is stopped a certain amount of gasoline will collect in the lower part of the passage 26 and form a convenient supply which will be readily available to provide a rich mixture for the motor when the same is started again.

It will be understood that various changes may be made in the details within the scope of the appended claims and therefore I do not wish to be limited to the precise details shown and described.

Having described my invention what I claim and desire to secure by Letters-Patent is,

1. In a carbureter, the combination of a choke tube, a fuel nozzle therein, an air

supply passage for the choke tube, a mixing chamber in communication with the choke tube, an auxiliary air inlet passage for said mixing chamber, a valve adapted to close said auxiliary air inlet, an air supply conduit communicating with said first mentioned air passage and said auxiliary air inlet passage, and an opening from the latter passage to the external atmosphere. 70

2. In a carbureter, the combination of a choke tube, a fuel supply nozzle therein, an air passage communicating with the choke tube, a mixing chamber communicating with the choke tube, an auxiliary air inlet passage for the mixing chamber, an opening from the latter passage to the external atmosphere, an air supply conduit communicating with said first mentioned air passage and said auxiliary air inlet passage, and valve means adapted to regulate the quantities of air supplied to the said auxiliary air inlet passage through the said opening and said conduit. 80

3. In a carbureter, the combination of a choke tube, a fuel supply nozzle therein, an air passage communicating with the choke tube, a mixing chamber communicating with the choke tube, an auxiliary air inlet passage for the mixing chamber, an opening from the latter passage to the external atmosphere, an air supply conduit communicating with said first mentioned air passage and said auxiliary air inlet passage, and a valve adapted to close said opening or cut off communication between said air conduit and said auxiliary air inlet passage. 90 95

4. In a carbureter, the combination of a choke tube, a fuel supply nozzle therein, an air passage communicating with the choke tube, a mixing chamber communicating with the choke tube, an auxiliary air inlet passage for the mixing chamber, an opening from the latter passage to the external atmosphere, an air supply conduit communicating with said first mentioned air passage and said auxiliary air inlet passage, and a valve adapted to regulate the quantities of air supplied to said auxiliary air inlet passage through said opening and said air supply conduit. 105 110

5. In a carbureter, the combination of a choke tube, a nozzle therein, an air supply passage communicating with the choke tube, a mixing chamber communicating with the choke tube, an auxiliary air inlet for the mixing chamber, a valve adapted to close said inlet and also regulating the flow through the choke tube, a plurality of springs adapted to regulate the opening of said valve, and independently actuated wedge devices for adjusting the action of said springs. 115 120 125

6. The combination of air heating means, a carbureter having main and auxiliary air inlet passages, a pipe establishing communi- 130

cation between said means and both of said passages, an opening from said auxiliary air inlet passage to the external atmosphere, and means for regulating the temperature of the 5 air supply through said auxiliary air inlet passage by mixing air from said pipe with cooler air drawn through said opening.

7. The combination of air heating means, a carbureter having main and auxiliary air 10 inlet passages, said auxiliary passage having an opening to the external atmosphere, a pipe establishing communication between said means and both of said passages, and means for regulating the temperature of the 15 air supply through said auxiliary passage by varying the amount of air admitted directly thereto from the external atmosphere.

8. The combination of air heating means, a carbureter having main and auxiliary air 20 inlet passages, a pipe establishing communication between said means and both of said

passages, means for regulating the temperature of the air in said pipe, and additional means for regulating the temperature of the air in said auxiliary passage.

25

9. The combination of air heating means, a carbureter having main and auxiliary air inlet passages, a pipe establishing communication between said means and both of said 30 passages, means for admitting air from the external atmosphere to said pipe in varying amounts to regulate the temperature of the air in said pipe, and means for admitting air from the external atmosphere to said auxiliary passage to regulate the temperature of the air therein.

In testimony whereof I affix my signature in presence of two witnesses.

SIDNEY D. WALDON.
